UNITED STATES PATENT OFFICE.

BENJAMIN W. CHASE, OF JACKSON, MICHIGAN, ASSIGNOR TO HIMSELF AND
A. E. HAWLEY, OF SAME PLACE.

IMPROVEMENT IN RUNNING-GEAR FOR VEHICLES.

Specification forming part of Letters Patent No. **156,134**, dated October 20, 1874; application filed
April 7, 1874.

To all whom it may concern:

Be it known that I, BENJAMIN W. CHASE, of Jackson, in the county of Jackson and State of Michigan, have invented an Improvement in Wagons, of which the following is a specification:

The nature of this invention relates to certain improvements in the construction of wagons, more especially those made with wooden axles; and it has for its object to prevent the great wear upon the axles and sand-boards by abrasion by the reach and king-bolt, as more fully hereinafter described.

Figure 1 is a perspective view of the forward axle, showing my improvement attached. Fig. 2 is a horizontal section. Fig. 3 is a detached perspective of one of the wear-plates. Fig. 4 is a detached view of one of the sustaining-bolts.

Like letters indicate like parts in each figure.

In the drawings, A represents the axle; B, the sand-board; C, the hounds, and E the king-bolt, all of the usual form and construction, except as hereinafter mentioned. F F' are wear-plates, the former of which rests on the upper face of the axle, and the latter on the under face of the sand-board. These wear-plates are alike, and are provided with flanges a, which, being let into the adjacent wooden parts, assist in securing the plates in place. They are also provided with hollow studs b, the interior diameter of which should be of sufficient diam-

eter to admit the king-bolt. These hollow studs are let into axle and sand-board to form linings for the holes bored in said axle and sand-board for the king-bolt. Near the ends of these plates they are provided with holes c, through which the sustaining-bolts G are passed, the posts d being sleeved on said bolts, with their ends resting on the plates, as shown, at each end, to support the sand-board. The plates are also provided with circular or curved flanges e, to protect the posts d from being sprung by contact with the reach H, in cramping or turning the wagon. Into the king-bolt hole, through the end of the reach, is inserted a flanged tube, f, of proper size, which projects just far enough through to the opposite side to engage with a washer, and be riveted thereto, forming an "eyelet," and preventing the wear of the king-bolt on the reach.

What I claim as my invention, and desire to secure by Letters Patent, is—

The combination, with the axle A and sand-board B, of the wear-plates F F', having the hollow stud b and flange e, the sustaining-bolts G, having posts d, the reach H, having flanged tube f and washer, and the king-bolt E, all constructed and combined substantially as described and shown.

BENJAMIN W. CHASE.
